[57] **CLAIM**

The ornamental design for a pallet, substantially as shown and described.

DESCRIPTION

FIG. 1 is a top plan view of a pallet showing our new design;

FIG. 2 is a bottom plan view thereof;

FIG. 3 is a perspective view thereof;

FIG. 4 is an end elevation view thereof; and

FIG. 5 is a side elevation view thereof.

The side and end not shown are the same as those which are shown.
